UNITED STATES PATENT OFFICE.

HARRY W. TROUT, OF SYRACUSE, NEW YORK, ASSIGNOR TO COTSWOLD COMFORTABLE COMPANY, OF SYRACUSE, NEW YORK, A CORPORATION OF NEW YORK.

GARNETT MACHINE.

Application filed February 17, 1923. Serial No. 619,780.

To all whom it may concern:

Be it known that I, HARRY W. TROUT, a citizen of the United States of America, of Syracuse, in the county of Onondaga, in the State of New York, have invented new and useful Improvements in Garnett Machines, of which the following, taken in connection with the accompanying drawings, is a full, clear, and exact description.

10 This invention relates to certain improvements in Garnett machines.

The primary object of the invention is to provide automatically operating means for controlling the supply of the raw material, such as cotton, wool, etc., to such machine in accordance with the needs of the machine, and more specifically an intermittent feed by means of which a substantially predetermined amount of the raw material is supplied to the machine at each feeding operation, such a feeding operation being initiated at a substantially predetermined interval of consumption of the raw material by the machine.

25 By this apparatus an operating supply of raw material is always maintained in the hopper of the machine by reason of the fact that the feed is controlled by the presence or absence of a substantially predetermined amount of raw material in the hopper of the machine. Manual feeding of the machine is entirely eliminated by the apparatus of this invention, not only assuring continuous operation of the machine, but effecting a material saving in the expense of operation.

30 Other objects and advantages relate to the details of the apparatus, all as will more fully appear from the following description, taken in connection with the accompanying drawings in which:

Figure 1 is an elevation, partially broken away, of an apparatus of my invention.

45 Figure 2 is an elevation at right angles to Figure 1, of the means for conveying raw material to the hopper of the Garnett machine.

Figure 3 is an elevation of a portion of the sectional hopper.

50 Figure 4 is a section taken on line 4-4, Figure 1.

Figure 5 is a rear end elevation of the machine.

Figure 6 is a view of the mutilated gear and portions of its actuating mechanism.

55 In the drawings only those portions of a

Garnett machine are shown which have a direct relation to the novel features of the apparatus.

The hopper —1— of the machine of this invention is formed in two relatively movable sections or with a movable wall preferably substantially as shown, the section —1— being stationary with the machine, while the section —2— is pivoted on bolts —3— at opposite sides of the stationary section —1— and at the lower end thereof for relative tilting movement with respect to the section —1— as controlled by bolts —4— projecting inwardly from opposite sides of the upper portion of the section —1— and positioned respectively in the slots —5— formed in the upper portion of the movable section —2—. The slots —5— may be formed upon an arc which has for its radius a straight line connecting the axis of the bolts —3— and —4—. For the purpose of normally maintaining the section —2— in its retracted position, a bell crank lever —6— is provided at opposite sides of the machine pivoted upon a bolt or stud —7— mounted on the stationary section —1—, the end —8— of such lever being connected by a link —9— with the movable section —2—, preferably near the upper rear portion thereof, as illustrated, so that rocking of the bell crank lever —6— will move the section —2— to its inner and outer position as limited by slots —5— moving on the bolts —4— and for the purpose of normally holding the section —2— in retracted position, a weight —39— is provided mounted upon the forward end of the bell crank lever —6— and preferably adjustable thereon so that the section —2— can be maintained in retracted position with the degree of force desired, and this for the reason that the operation of the movable wall or section —2— of the hopper is adapted to be effected by the weight of the raw material, such as cotton or wool supplied to the hopper, and it may be desirable to restrain the movement of the section —2— to permit the hopper to fill to various extents to meet various conditions, and this can be effected by adjusting the weight —39—.

Any suitable means for supplying raw material to the hopper —1— under the control of mechanism such as that hereinafter described may be utilized, but the preferred form of my invention includes a continuously moving belt conveyor —10— to which

sufficient raw material is at all times supplied, so that there is raw material enough moving at all times across the valve —11— for maintaining the continuous operation 5 of the Garnett machine. As illustrated, the raw material is moved across the valve —11— upon the return movement of the belt conveyor, but any arrangement suitable for the purpose may be substituted for the 10 one shown. The valve —11— controls communication between the housing —12— for the belt-conveyor —10— and the chute or conduit —13— adapted to convey a raw material when supplied thereto to the hopper —1— of the Garnett machine. The communication between the housing —12— and the chute —13— is controlled, as before suggested, by the valve —11— which is normally maintained in closed position by the 15 lever —14— which carries the valve, such lever including means, as the weight —15— for normally overbalancing the valve, and holding it in closed position to cut off communication between the housing —12— and the chute —13—. As shown, the belt-conveying mechanism may be arranged upon one floor of a building, while the Garnett machine is arranged on another floor, as for instance, a lower floor, and the chute 20 —13— may extend through the floor for supplying raw material to the Garnett machine by gravity feed.

Means is provided for opening the valve —11— against the action of the weight 25 —15— when the raw material in the hopper —1— has been consumed or taken up by the Garnett machine to a substantially predetermined extent, and this means includes, as illustrated, a flexible cable —16— connected at one end to lever —14— and at its other end by link —17— to the rim of the mutilated gear —18—. This gear —18—, as illustrated, has two segmental portions formed with gear teeth separated by two 30 substantially diametrically disposed portions —19— and —20— that are not equipped with gear teeth, so that when the portion —19— is moved to the position shown in Figure 6, no further rotation of 35 the gear —18— will take place until the tooth —21— is moved, as hereinafter described, rotarily forward a sufficient distance to bring it into mesh with the teeth of the continuously moving driving gear —22—.

50 In the position shown in Figure 6, the valve —11— is maintained in closed position by the weight —15—. When, however, the tooth —21— is moved forwardly into mesh with the gear —22— a rotation of gear 55 —18— is effected until the smooth section —20— of the gear —18— is rotated substantially 180 deg. and is moved opposite the teeth of the gear —22—, at which time no further rotation of gear —18— will be effected until tooth —23— is moved for-

wardly a sufficient distance so as to be brought into mesh with the teeth of the driving gear —22—.

During this stationary condition of gear —18— the portion of the gear —18— to 70 which link —17— is connected will be disposed at the lower side of the gear and at a point substantially 180 deg. from the position illustrated in Figure 6. The rotary movement of the gear, as described, will therefore, draw the flexible cable —16— downwardly, overcoming the gravity of weight —15— and open the valve —11— to permit the discharge of cotton, wool or other raw material through the chute —13— 80 to the hopper —1—.

The operation of the gear —18—, so as to effect a rotary movement of that gear to bring the tooth —21— and the tooth —23— intermittently into mesh with gear —22—, 85 is effected as before indicated by movement of the movable section —2— of the hopper as effected by gravity of the raw material in the hopper. As described, normally the hopper section —2— is retracted by means of weight —39— and at that time, the valve —11— is open permitting the discharge of raw material into the hopper. As the raw material builds up in the hopper, its gravity overcomes the weight —39— and gradually 90 moves the movable section —2— toward its expanded position. The opening movement of the section —2— effects a slight rotary movement of the gear —18— through the medium of a ratchet —24— that has one end pivoted to the forward end of the bell crank lever —6— by means of pin —25—. The lower end of this ratchet —24— is formed with a notch preferably substantially as illustrated in Figure 6, which engages 100 the pin or tooth —26—, which extends axially from the rim of the gear —18—. The notch —27— is of such form that it will operate to rotate the gear in a counter clock-wise direction in Figure 6, but is 105 formed with an elongated inclined surface which will permit the continued rotation of the gear —18— when the tooth —21— has been brought into mesh with the gear —22—, the pin —26— moving along the cam 110 surface of the notch —27— and forcing the pawl —24— outwardly to permit the passage of the pins —26—.

This rotary movement of the gear continues through substantially 180 deg. and 115 until the untoothed portion —20— is moved opposite the gear —22—, at which time the pin —26— will seat itself in the notch —28— in a second pawl —29—, preferably the notch —28— is of substantially the same 120 form as the notch —27—.

125 It will be noted that by this rotary movement just described the valve —11— is opened and raw material will be fed to the hopper. The weight of such material in the 130

hopper will gradually tilt the section —2— outwardly raising the weighted end of the bell crank lever —6—, and thereby raising the pawl —29— pivoted on the pin —25— in like manner as the pawl —24—. This raising movement of pawl —29— which engages the pin —27— will bring the tooth —23— into mesh with the gear —22— when a sufficient weight of raw material has been received in the hopper to move the section —2— to substantially the limit of its expandable position, and at that point another rotation of the gear —18— through substantially 180 deg. will be effected to again bring the link —17— to position shown in Figure 6 and permit the closing of the valve —11— by gravity movement of weight —15—. For the purpose of holding the pawls —29— in proper relation to engage pin —26— and yet to permit some spreading action, whereby the notches in the pawls are disengaged with the pin —26—, the two pawls are extended downwardly through a guide plate —30— which may be secured to the stationary section of the hopper, and is formed with two slots —31— and —32— the slot —31— receiving the pawl —29— and the slot —32— receiving the pawl —24—, the slots being of somewhat greater length than the width of the pawls, and for the purpose of holding the pawls resiliently in engagement with the pin —26— in its respective positions, a coil spring —33— is provided preferably positioned below the plate —30— and connecting the adjacent portions of the pawls —24— and —29—, for drawing them toward each other, but permitting their separation under the camming action of the pin —26— acting on the wall of the notch —27— or the wall of notch —28—.

The operation of the apparatus will be understood from the above description, the essential features of the structure being a movable wall or section in connection with a hopper which by its movement dependent upon the weight of the raw material in the hopper, controls the feed of raw material to the hopper, and altho I have shown and described a specific construction as illustrative of an embodiment of my invention, I do not desire to limit myself to the details of construction, form, or arrangement of the same, as various changes may be made without departing from the invention as set forth in the appended claims.

I claim:

1. In a Garnett machine, a hopper including a movable part, hopper-supplying means, a continuously rotating part, and a second rotary part rotarily actuated by the continuously rotating part only at predetermined positions of said movable part for varying said supplying means.

2. In a Garnett machine, a hopper in-

cluding a movable part, hopper-supplying means, a valve controlling such means, a continuously rotating part and a second rotary part rotarily actuated by the continuously rotating part only at predetermined positions of said movable part for opening and closing said valve.

3. In a Garnett machine, a hopper including a movable part, hopper-supplying means having a valve controlling such means, a continuously rotating part, a rotary valve-operating mechanism out of driving engagement with said continuously rotating part when the said valve is open or closed, and means actuated by said movable part when moved from one of its positions to another for bringing said valve-operating means into driving engagement with said continuously rotating element to reverse the position of the valve.

4. In a Garnett machine, a hopper including a movable part, hopper-supplying means, a continuously rotating part and mechanism for controlling said hopper-supplying means including a second rotary part rotarily out of driving engagement with said continuously rotating part when the movable part is at the limit of either its opening or closing movements.

5. In a Garnett machine, a hopper including a movable part, hopper-supplying means, a continuously rotating part and mechanism for controlling said hopper-supplying means including a rotary part out of driving engagement with said continuously rotating part when the movable part is at the limit of either its opening or closing movements, said member being brought into driving engagement with said continuously rotating part when the movable part is moved from one position to another, dependent upon the presence or absence of supplied substance in the hopper.

6. In a Garnett machine, a hopper comprising a stationary section and a movable section, a lever pivotally mounted on the stationary section and connected with the movable section, a weight on said lever for normally holding said movable section in its retracted position, a pair of pawls pivotally secured to said lever, a spring connecting the pawls for maintaining them in proper relation, a valve-actuating member having a pin thereon for engagement with either of said pawls, means for driving said valve-actuating member which is brought into driving relation with the actuating member only when the latter has been shifted through engagement of one of said pawls with said pin.

7. In a Garnett machine, a hopper comprising a stationary section and a movable section, means for supplying raw material to the hopper, a valve controlling such supply, a mutilated gear connected to said valve

- for opening the valve, and means for driving said mutilated gear intermittently to actuate said valve.
8. In a Garnett machine, a hopper comprising a stationary section and a movable section, means for supplying raw material to the hopper, a valve controlling such supply, a mutilated gear connected to said valve for opening the valve, and means for effecting movement of said mutilated gear in accordance with movement of the movable section of the hopper.
9. In a Garnett machine, a hopper having a movable wall, a driving gear, a mutilated gear adapted to be intermittently driven thereby, and means for moving said mutilated gear to bring its gear segments into mesh with said driving gear in accordance with movement of the movable section 20 of the hopper.
10. In a Garnett machine, a hopper having a movable wall, a driving gear, a mutilated gear adapted to be intermittently driven thereby, means for moving said mutilated gear to bring its gear segments into mesh with said driving gear in accordance with movement of the movable section of the hopper, means for supplying raw material to the hopper, a valve controlling such supply, and a connection between said valve and said mutilated gear.
11. In a Garnett machine, a hopper comprising a stationary part and a movable part pivoted at its lower end to the stationary part and adapted to swing outwardly at its upper end, means connecting the upper end of the movable part to the adjacent portion of the stationary part and permitting limited relative movement of said parts about their pivotal connection, and means actuated by movement of the movable part with respect to the stationary part for controlling the supply of raw material to the hopper.
- 45 12. In a Garnett machine, a hopper comprising a stationary part and a movable part pivoted at its lower end to the stationary
- ary part and adapted to swing outwardly at its upper end, means connecting the upper end of the movable part to the adjacent portion of the stationary part and permitting limited relative movement of said parts about their pivotal connection, a lever pivoted to the stationary part and connected to the movable part, and means actuated by movement of said lever for controlling the feed of material to the hopper.
13. In a Garnett machine, a hopper comprising a stationary part and a movable part pivoted at its lower end to the stationary part and adapted to swing outwardly at its upper end, means connecting the upper end of the movable part to the adjacent portion of the stationary part and permitting limited relative movement of said parts about their pivotal connection, a continuously rotating part, a lever pivotally secured to the stationary part and having a connection with the movable part of the hopper, and a member moved into driving relation with the continuously rotating part by said lever to thereby control the feed of material to the hopper.
14. In a Garnett machine, a hopper comprising a stationary part and a movable part pivoted at its lower end to the stationary part and adapted to swing outwardly at its upper end, means connecting the upper end of the movable part to the adjacent portion of the stationary part and permitting limited relative movement of said parts about their pivotal connection, a continuously rotating gear, a bell-crank lever pivoted to the stationary part and having one end connected to the movable part, a mutilated gear, and means actuated by the lever for bringing the teeth of the mutilated gear into mesh with the continuously rotating gear to control the supply of material to the hopper.

In witness whereof I have hereunto set my hand this 13th day of February, 1923.

HARRY W. TROUT.
